HENRY ZAJAC, OF PASSAIC, NEW JERSEY.

LAMP-EXTINGUISHER.

1,400,845.

Specification of Letters Patent. Patented Dec. 20, 1921.

Application filed June 1, 1921. Serial No. 474,057.

To all whom it may concern:

Be it known that I, HENRY ZAJAC, a citizen of Poland, residing at Passaic, in the county of Passaic and State of New Jersey, have invented certain new and useful Improvements in Lamp-Extinguishers, of which the following is a specification.

This invention relates to improvements in lamp burners and has for its principal object to provide a device which will enable the lamp to be lighted without necessitating the removal of the chimney.

Another object is to provide an improved burner so constructed as to enable the burning end of a match or similar igniting device to be placed in contact with the wick with ease.

With these and other objects in view the invention consists in the novel construction, combination and arrangement of parts which will be fully set forth in the following specification, claimed and illustrated in the accompanying drawing, in which,

Figure 1 is a top plan view of this improved burner,

Fig. 2 is a perspective view of the chimney supporting ring, a portion thereof being broken away, and

Fig. 3 is a vertical sectional view through the burner.

Referring to the drawings in detail the numeral 10 designates the burner base provided with the customary wick tube 11 and the chimney securing prongs 12. A wall 13 provided with the customary perforations is arranged at the upper end of the base and surrounds the wick tube as clearly shown in Fig. 3. As shown this wall extends downwardly and outwardly and is provided with an annular flange 14 upon which the chimney supporting ring rests.

The chimney supporting ring is designated generically by the numeral 15 and comprises a tubular body 16 provided near its upper end with an inwardly extending annular flange 17 forming the support for the chimney. An opening 18 is formed in the body 16 beneath the flange and an inwardly extending collar 19 surrounds said opening. The upper wall of said collar inclines upwardly as shown in the drawings to enable the igniting element to be readily moved

into contact with the wick, and it will be seen that the inner end of said collar is disposed inwardly beyond the inner edge of the flange 17 for a purpose to be more fully hereinafter set forth.

Formed in the base 10 at a point between the planes of the flat faces of the wick tube 11 is a guide opening for the reception of a rod 20, the lower end of which is provided with an angular extension 21 forming a thumb piece. A coil spring 22 surrounds the rod near its lower end and is so arranged as to tend to force the same downwardly. Secured to the upper end of the rod is an arm 23 formed at its inner end with a ring 24 in which the burner cap 25 is riveted or otherwise secured. A guard plate 26 is riveted near the lower edge of the burner cap 25 and is provided with a downward extension forming a shutter 27 which frictionally engages the inner end of the collar 19 as shown in Fig. 3.

In use it will be seen that when it is desired to light the lamp, pressure is applied to the thumb piece 21 whereby the rod 20 will move upwardly thereby lifting the burner cap and opening the shutter 27 so that a lighted match may be introduced through the opening 18. Obviously the chimney cannot become smoked by the flame of the match owing to the length of the collar 19 and the fact that the guard plate closes the distance between the end of the collar and the burner cap. After the lamp is lighted, the match is withdrawn and upon releasing the pressure on the thumb piece it will be seen that the burner cap 25 will descend under the influence of the spring 22, thus returning the parts to normal position and closing the opening 18.

While in the foregoing there has been shown and described the preferred embodiment of this invention, it is to be understood that minor changes in the details of construction, combination and arrangement of parts may be made without departing from the spirit and scope of the invention as claimed.

What is claimed is:—

A lamp burner comprising a base, a wick tube extending therethrough, chimney securing prongs carried by the base, a chimney

supporting ring associated with the base, said ring having an opening therein, an inwardly extending collar surrounding the opening, a burner cap associated with the base, a shutter carried by the burner cap for closing the opening in the ring, spring pressed means to normally hold the burner

cap downwardly and the shutter in closed position, an extending handle for elevating the burner cap from the exterior of the lamp burner.

In witness whereof I affix my signature.

HENRY ZAJAC.
